CLAIM

We claim the ornamental design for an insert for an air cleaner cover, as shown and described.

DESCRIPTION

FIG. 1 is a perspective view of an insert, embodying aspects of the invention.

FIG. 2 is a right-side view of the insert of FIG. 1.

FIG. 3 is a left-side view of the insert of FIG. 1.

FIG. 4 is a top view of the insert of FIG. 1.

FIG. 5 is a bottom view of the insert of FIG. 1.

FIG. 6 is a front view of the insert of FIG. 1.

FIG. 7 is a rear view of the insert of FIG. 1.

FIG. 8 is a perspective view of an insert, embodying aspects of the invention.

FIG. 9 is a right-side view of the insert of FIG. 8.

FIG. 10 is a left-side view of the insert of FIG. 8.

FIG. 11 is a top view of the insert of FIG. 8.

FIG. 12 is a bottom view of the insert of FIG. 8.

FIG. 13 is a front view of the insert of FIG. 8; and,

FIG. 14 is a rear view of the insert of FIG. 8.

The portions of the insert shown in broken lines are included for the purpose of illustrating environment and form no part of the claimed design.
